UNITED STATES PATENT OFFICE

2,418,386

CONTINUOUS PICKLING AND CLEANING
DEVICE FOR METAL

Frank J. Wood, Riverside, Ill., assignor to Goodman Manufacturing Company, Chicago, Ill., a corporation of Illinois

Application January 17, 1942, Serial No. 427,092

5 Claims. (Cl. 134—99)

1

This invention relates to improvements in continuous pickling and cleaning devices for metal and more particularly relates to a new and improved means for facilitating the pickling operation.

The principal objects of my invention are to provide a novel circulating and conducting means for the pickling fluid in the pickling trough, so arranged as to circulate fresh pickling fluid across the upper and lower surfaces of the metal at a high velocity, to insure that the entire surfaces of the metal are washed with fresh pickling fluid at all times during the pickling operation.

A more specific object of my invention is to provide a pickling trough having pickling fluid inlets spaced at intervals along the trough, above and below the path of travel of the metal therethrough with a deflecting means at the bottom of the trough, to deflect fluid discharged from the lower fluid inlets and to cause it to move in substantially recurrent paths and assume a whirlpool action, together with fluid inlets entering the trough above the path of travel of the metal therethrough and adapted to direct pickling fluid into the trough transversely thereof in substantially recurrent paths so said fluid inlets will circulate fresh acid across both sides of the metal at a high velocity, at all times during the pickling operation.

A further object of my invention is to provide a novel form of pickling and cleaning trough with means for directing the pickling fluid into said trough in recurrent paths above and below the path of travel of the metal therethrough, together with means for aiding the fluid to travel in these recurrent paths and for accelerating the pickling action of the pickling fluid by directing a gaseous medium under pressure into the pickling fluid.

A still further object of my invention is to provide a means for removing pickling fluid from the strip metal as it leaves the pickling tank, by directing a gaseous medium under pressure on the top and bottom sides of the metal, in a direction to blow the pickling fluid from the metal.

Other objects of my invention will appear from time to time as the following specification proceeds and with reference to the accompanying drawings wherein:

Figure 1 is a top plan view of a pickling and

2

cleaning trough constructed in accordance with my invention;

Figure 2 is an enlarged fragmentary detail plan view of a portion of the device shown in Figure 1;

Figure 3 is a horizontal sectional view taken through the troughs and showing certain details of one of the pickling fluid discharge pipes entering the trough;

Figure 4 is a fragmentary transverse sectional view taken substantially along line 4—4 of Figure 1;

Figure 5 is a fragmentary transverse sectional view taken substantially along line 5—5 of Figure 1;

Figure 6 is a diagrammatic partial fragmentary longitudinal sectional view showing certain details of the means for removing pickling fluid from the metal; and

Figure 7 is an enlarged diagrammatic partial fragmentary longitudinal sectional view taken substantially along line 7—7 of Figure 1, showing certain details of the nozzles for removing pickling fluid from the metal.

In the drawings, an elongated pickling trough

25 10, adapted to have the metal pass therethrough, for pickling by a hot pickling solution, is shown as being mounted on and extending along a pickling tank 11, which receives pickling fluid discharged from the ends of said trough, where it is

30 recirculated into said trough by means of a suitable motor driven pump 12 of a usual construction. Pinch rolls indicated generally by reference character 13 are provided at the entering end of said trough, for pushing strip metal M

35 therethrough, and other pinch rolls 14 (see Figure 6) are provided at the discharge end of said trough for pushing the metal to the next adjacent station in the pickling and cleaning device. From said pinch rolls, the metal may pass

40 through scrubbing and brushing rolls indicated generally by reference character 15, for washing and brushing the metal and further pushing it through the system. The pickling and cleaning apparatus, of which the trough 10 is a portion, and the pinch and scrubbing and brushing rolls

45 are a part of a pickling and cleaning apparatus such as is generally illustrated and described in my prior Patent No. 2,141,732, so will not herein be shown or described in detail, except in so far

as is necessary to make my present invention readily understandable.

The pickling trough 10, as herein shown, is of a rectangular cross section open at its discharge end as indicated by reference character 10' in Figure 6 and having a similar opening at its entering end, to permit the strip metal to continuously pass therethrough. Said trough is provided with a plurality of abutting covers 16, 16, extending over the top thereof and mounted on opposite sides of said trough (see Figure 4), to prevent the spilling of pickling fluid from said trough during the pickling operation. Said pickling trough is preferably constructed from an acid resisting sheet metal such as stainless steel, and is provided with a plurality of parallel spaced blocks 17, 17, disposed therealong, for supporting the metal above the bottom of the trough as it travels therealong. Said blocks are mounted on longitudinally spaced transversely extending shafts 18, 18, mounted on their ends in the sides of said pickling trough, and may be made from any smooth material which will support the metal above the bottom of the trough and will not scratch it as it passes thereover during the pickling operation.

Referring now to the fluid connections, for conducting fluid into the pickling trough, a pipe 19 leads from the pump 12 to a pipe or header 20, which extends along the trough 10, adjacent one side thereof. The pipe 20 has connection with longitudinally spaced discharge pipes or nozzles 23, 23, which, as shown in Figure 2, extend into the pickling trough 10, through the sides thereof, and beneath the horizontal plane along which the metal travels through said pickling trough (see Figure 4), to direct pickling fluid under pressure into said trough in a transverse direction.

Angular deflectors 24, 24 are mounted at the bottom of said pickling trough, beneath the path of travel of the metal therethrough, on the opposite side of the longitudinal center line of the trough from the pipes 23, 23. The angle of said deflectors is such that when engaged by the pickling fluid discharged under pressure from the pipes 23, 23, said deflectors will deflect the pickling fluid in directions towards the discharge end of the trough and cause said fluid to travel in recurrent paths across the trough and back towards the side from which said pickling fluid enters the trough.

The pipe 20 also has connection with transversely extending discharge pipes or nozzles 25, 25 which lead into the pickling trough 10, through the sides thereof, and are arranged alternately with the pipes 23, 23 and are disposed above the path of travel of the metal through said pickling trough (see Figure 4). The ends of said pipes or nozzles 25, 25, as herein shown, are formed to be inclined in a direction towards the discharge end of said trough (see Fig. 3), to direct the fluid transversely across the metal in substantially recurrent paths and in the same direction as the fluid is deflected by the deflectors 24, 24.

A rapid continually agitated flow of pickling fluid is thus provided, which is circulated over the top and bottom sides of the metal, thus insuring that the entire surface of the metal is intimately washed by fresh acid at all times.

A pipe 27 extends along the opposite side of the pickling trough 10 from the pipe 20, above the path of travel of the metal therethrough, and has connection with a plurality of vertically spaced transversely disposed pipes or nozzles 29, 29

29' leading therefrom into the trough, above and below the path of travel of the metal through the trough (see Fig. 4). The nozzles 29, 29' are adapted to direct a gaseous medium under pressure into the pickling trough, above and below the path of travel of the metal through the trough from the side of said trough opposite from the nozzles 23 and 25. Valves 30, 30 are provided to control the amount of gas passing through said nozzles. The gaseous medium used may be of a kind which will accelerate the action of the pickling fluid and may be at room temperature, or may be heated if desired, to help maintain the pickling solution at the desired temperature. Air has been found to be a suitable medium, but the products of combustion of the blast furnace or any other suitable form of gas may be used. Said nozzles, directing a gaseous medium under pressure into the pickling solution from the opposite side thereof from which the pickling fluid is directed into said trough, thus serve to increase the whirlpool action and agitation of the pickling fluid, and the gas, besides increasing the agitation of the pickling fluid and breaking up any hydrogen bubbles, and preventing the formation of protective coatings or films, also accelerates the chemical action of the pickling fluid on the metallic oxides, and increases the speed of pickling.

A pipe 31 is herein shown as being connected to the pipe 27. Said pipe leads beyond the discharge end of the pickling trough 10 and has connection with a horizontally arranged transversely extending pipe or nozzle 33 (see Figures 1, 6 and 7). A transversely extending pipe 31' is arranged beneath the pipe 31 and extends in parallel relation with respect to said pipe 31. Said pipe 31' is connected to the pipe 27 (see Figure 6) and leads to a transversely extending nozzle or pipe 33' disposed beneath the nozzle 33. Said transversely extending nozzles are spaced forwardly of the discharge end of said pickling trough and extend transversely across the forward end thereof above and below the path of travel of the metal to the pinch rolls 14, 14 (see Figures 6 and 7). Said pipes, extending across the discharge end of said trough are in the form of a V in plan, the point of the V being on the longitudinal center line of the trough. Said upper pipe 33 has a slot 34 extending along the lower forward portion thereof and inclined downwardly towards the metal and the entering end of the trough, to direct air or any other gaseous medium on the metal at such an angle as to blow the pickling fluid therefrom. Said lower pipe 33' has a similar slot 34' formed therein, to direct air or gas under pressure on the lower side of the metal and blow excess pickling fluid therefrom.

It may be seen from the foregoing that heated or cold air, or a gaseous medium, may be directed against both sides of the metal as it leaves the pickling trough, in directions to remove all pickling fluid therefrom before the metal contacts the pinch rolls 14, 14, thus providing an efficient and simplified means for removing pickling fluid from the metal before it reaches the pinch rolls and for preventing the carrying over of the pickling fluid beyond the pinch rolls as the metal leaves the pickling trough and tank.

While I have herein shown and described one form in which my invention may be embodied, it will be understood that the construction thereof and the arrangement of the various parts may be altered without departing from the spirit and

scope thereof. Furthermore, I do not wish to be construed as limiting my invention to the specific embodiment illustrated, excepting as it may be limited in the appended claims.

I claim as my invention:

1. In an apparatus of the class described, a trough, a plurality of grid blocks disposed along said trough for slidably supporting an article above the bottom of said trough for treatment as it passes along said trough, and means for directing a treating solution to flow across said trough at a high velocity with a whirlpool action at a plurality of places along said trough, above and below the path of travel of the article being treated through said trough, including a plurality of fluid conducting pipes entering said trough along one side thereof above and below the horizontal plane in which the material supporting surfaces of said blocks lie, and adapted to discharge fluid under pressure into said trough in a transverse direction with respect thereto, and other pipes entering said trough along the opposite side thereof from said first mentioned pipes above and below the horizontal plane in which the material supporting surfaces of said blocks lie, for discharging fluid under pressure into said trough in a transverse direction with respect thereto.

2. In an apparatus of the class described, a trough, a plurality of grid blocks disposed along said trough for slidably supporting an article above the bottom of said trough for treatment as it passes along said trough, and means for directing a treating solution across said trough at a high velocity with a whirlpool action at a plurality of places along said trough, above and below the path of travel of the article being treated through said trough, including a plurality of fluid conducting pipes entering said trough from one side thereof above and below the horizontal plane in which the material supporting surfaces of said blocks lie, and deflectors along the bottom of said trough adapted to be engaged by the streams of treating fluid discharged from the pipes along the bottom of said trough, to deflect the fluid discharged therefrom and cause it to travel in substantially recurrent paths, and said pipes above the horizontal plane in which the material supporting surfaces of said blocks lie being directed at obtuse angles to the sides of said trough, to cause the pickling fluid to travel in recurrent paths in the same direction as the paths of the fluid discharged below the horizontal plane in which the material supporting surfaces of said blocks lie.

3. In an apparatus of the class described, a trough, a plurality of grid blocks disposed along said trough for slidably supporting an article above the bottom of said trough for treatment as it passes along said trough, and means for directing a treating solution across said trough at a high velocity with a whirlpool action at a plurality of places along said trough, above and below the path of travel of the article being treated through said trough, including a plurality of fluid conducting pipes entering said trough below the horizontal plane in which the material supporting surfaces of said blocks lie and adapted to discharge fluid under pressure into said trough in a transverse direction with respect thereto, other pipes arranged alternately with said first mentioned pipes above the horizontal plane in which the material supporting surfaces of said blocks lie, for discharging fluid under pressure into said trough in a transverse

direction with respect thereto, and a plurality of longitudinally and vertically spaced nozzles entering said trough above and below the horizontal plane in which the material supporting surfaces of said blocks lie, arranged to discharge a gaseous medium into said treating solution at a high velocity, to aid in directing the treating fluid in recurrent paths and to facilitate the treating action of said treating solution.

10. 4. In an apparatus of the class described, a trough through which the article to be treated is adapted to pass, a plurality of grid blocks disposed along said trough for slidably supporting an article above the bottom of said trough for treatment as it passes along said trough, and means for washing a treating solution across said trough above and below the path of travel of the article to be treated through said trough, including a plurality of fluid conducting pipes entering said trough below the horizontal plane in which the material supporting surfaces of said blocks lie, and adapted to discharge fluid under pressure into said trough in a transverse direction with respect thereto, other pipes arranged alternately with said first mentioned pipes above the horizontal plane in which the material supporting surfaces of said blocks lie, for discharging fluid under pressure into said trough in a transverse direction with respect thereto, and angular deflectors in the bottom of said trough adjacent the side thereof opposite said lower pipes and in alignment with said lower pipes, said deflectors being adapted to deflect the treating fluid discharged from said pipes and to cause it to travel in recurrent paths across the article being treated, during travel thereof along said trough, and said pipes above the horizontal plane in which the material supporting surfaces of said blocks lie being at an angle to the sides of said trough to discharge the fluid transversely of said trough in the direction of travel of the article being treated through said trough.

5. In an apparatus of the class described, a trough through which the article to be treated is adapted to pass, a plurality of grid blocks disposed along said trough for slidably supporting an article above the bottom of said trough for treatment as it passes along said trough, and means for washing a treating solution across and above and below the article to be treated with a whirlpool action, as it passes through said trough including a plurality of fluid conducting pipes entering said trough below the horizontal plane in which the material supporting surfaces of said blocks lie and adapted to discharge fluid under pressure into said trough in a transverse direction with respect thereto, and other pipes arranged alternately with said first mentioned pipes above the horizontal plane in which the material supporting surfaces of said blocks lie, for discharging fluid under pressure into said trough in a transverse direction with respect thereto, angular deflectors in the bottom of said trough in alignment with said lower pipes and adapted to deflect the fluid discharged from said pipes in the direction of travel of the article to be treated through said trough, to cause the treating fluid to follow substantially recurrent paths, the ends of said pipes disposed above the horizontal plane in which the material supporting surfaces of said blocks lie being directed to discharge the fluid transversely of said trough in the direction of travel of the article to be treated through said trough, and a plurality of longitudinally and vertically spaced nozzles arranged

to enter said trough from the side thereof opposite from said fluid discharge pipes, above and below the horizontal plane in which the material supporting surfaces of said blocks lie, for directing streams of air into the treating solution in a direction transversely of said trough, to aid in causing the treating solution to travel in recurrent paths across the article being treated and to facilitate the treating action of the treating solution.
